ada

Application June 11, 1937, Serial No. 147,752
In Canada March 2, 1937

1 Claim. (Cl. 2—74)

Our invention relates to improvements in uniforms, dresses and like garments, and the object of the invention is, in a garment having its skirt front divided, to provide overlapping portions which may be reversed in position, to device an upper or blouse portion having its front overlapped to correspond in position with the overlapping of the skirt at each side its vertical centre, and a means for detachably securing the overlapped blouse portion in either of such overlapping positions, and it consists essentially of the arrangement and construction of parts all as hereinafter more particularly explained.

Fig. 1 is a front elevation of our garment, portions being broken away to exhibit the construction thereof.

Fig. 2 is a plan sectional view on line 2—2 Fig. 1.

Fig. 3 is a vertical sectional view on line 3—3 Fig. 1.

Fig. 4 is a transverse sectional view on line 4—4 Fig. 3.

Fig. 5 is an enlarged perspective detail of the button strip.

In the drawing like letters of reference indicate corresponding parts in the different views.

1 indicates the upper or blouse portion of a garment and 2 the skirt portion. The blouse portion 1 is divided to form overlapping portions 1^x and 1° so as to provide for a vertical centre opening.

3 are button holes formed in the overlapping portion 1^x and 4 are button holes formed in the underlying portion 1°. The button holes 3 and 4 are arranged in pairs which are aligned one with the other and behind these button holes is located an independent fabric strip 5 to which are secured buttons 5^x which are passed through aligned button holes 3 and 4 to secure the overlapping portions of the blouse together.

40 The skirt portion 2 is provided at each side its centre front with lateral extensions 6 and 7 which overlap and which are secured at their outer edge to each side of the skirt by any suitable means such as by ties 8 and 9. If ties are used the skirt is provided on its waist line with slotted openings 8^x and 9^x. When the garment is in the position shown with the skirt portion 6 overlapping the skirt portion 7, the tie 8 extends through the slotted opening 8^x and is passed around to tie 50 with the other tie portion 9 at the back of the wearer.

Also when the garment is in this position, the

portion 1^x of the blouse overlaps the portion 1°. If it is desired to reverse the garment, the buttons 6 are removed from the button holes 3 and 4 so that the strip 5 is detached from the garment and yet will hold the buttons together. The tie 8 is withdrawn from the slot 8^x and the skirt extension 7 is folded to the outside of the extension 6, the portion 1° of the blouse then overlying the portion 1^x in the reverse position to that which it previously assumed. The button strip is then placed at the back of the overlapping portions 1^x and 1° and the buttons passed through the button holes 3 and 4.

When this is done, the tie 9 is passed through the slotted opening 9^x and passed with the tie 8 to the back of the wearer to be tied in suitable manner.

From this description it will be seen that we have devised a very simple construction which will provide a garment having an overlapping skirt with a blouse which will have a vertical centre opening, the edges of which are overlapped and detachably secured together by any suitable means such as the button 5^x described.

If desired a double breasted effect may be produced by extending the overlapping portions 1^x and 1° laterally and providing aligned button holes in the overlapping portions adjacent each vertical edge and aligned button holes in the blouse and securing these parts together with buttons and button strips such as 5^x and 5 previously described, a button strip being provided at each side of the blouse.

What we claim as our invention is:—

In a wraparound garment, a skirt having a double front formed by overlapping portions extending to opposite sides of the skirt, a waist formed integral with the skirt and having a centre front opening the sides of which overlap, registering button holes in the overlapping and underlapping portions, a removable tape extending beneath the lapping portions and having a single row of buttons extending longitudinally thereof, each button insertable in a pair of registering button holes imparting a shirt front effect to the wraparound garment whereby the front skirt portion and central front portion of the waist may be overlapped to present either portion outermost.
